UNITED STATES PATENT OFFICE.

OLIVER LONG, OF BROOKLYN, N. Y., ASSIGNOR OF ONE-HALF TO CHARLES SCHLÜTER AND CHARLES FORSTER, BOTH OF NEW YORK, N. Y.

MATERIAL FOR PACKING BOTTLES.

SPECIFICATION forming part of Letters Patent No. 300,323, dated June 10, 1884.

Application filed June 29, 1883. (No model.)

To all whom it may concern:

Be it known that I, OLIVER LONG, of the city of Brooklyn, in the county of Kings and State of New York, have invented a new and useful Material for Packing Bottles; and I do hereby declare that the following is a full, clear, and exact description of the same, reference being had to the accompanying drawings, forming a part of this specification.

10 My invention consists in an improvement in the packing material placed between bottles made by placing in the recesses of contiguous paper wrappers hay or straw, so made as to form pads, which are placed between the

15 bottles or wrapped around them.

In the drawings, Figure 2 represents a plan view of a piece of the packing material, in which the paper wrapper is shown at A, and the recesses in the wrappers filled with hay or straw are shown at B. Fig. 3 is a vertical section of the same piece of packing along the plane of the line yy in Fig. 2, and more clearly shows the arrangement of the straw or hay in the recesses in the wrapper. For convenience such a piece of packing is called a "pad." Fig. 1 shows three bottles, C C C, with pads placed between them and preventing their contact. Fig. 4 is a top plan view of a box filled with bottles and protected by the pads.

25 This view more clearly indicates the method of using this material.

The pads of suitable size are placed in an upright position against the sides of the box and between the rows, the bottles being prevented from touching each other laterally by means of smaller pads inserted between them at right angles to the former row of pads. The bottoms and tops of the bottles are protected by placing next to them sheets of straw-board, card-board, or wood, as shown at a in Fig. 1, and placing large pads between such

sheets of card-board and the bottom and lid of the box or case.

In the packing of bottles the only parts that need protection are the bottom, the top, and the lines of contact with the adjacent bottles and with the sides of the box. If this purpose is accomplished, all packing material between the bodies and necks of the bottles is superfluous, and only increases the weight of the package and the expense of the packing. Straw is the most perfect packing material, especially in its unbroken tubular form, remaining always elastic and unaffected by moisture, as in a ship's hold. Straw, however, causes more or less litter or dirt, and is objectionable on that account. By the use of my invention the bottles are perfectly protected at their lines of contact with each other and with the sides of the box. No superfluous material is employed, and the weight and bulk of the packed case is little more than when filled with the bottles alone. It is not affected by moisture, there is no litter, as the straw cannot escape, and the material may be repeatedly used. By using the method of packing above described there is also a material saving of time and labor.

Having thus described my invention, what I claim as new is—

As an article of manufacture, a material composed of two sheets of paper, each sheet having recesses or corrugations, secured together with the recesses in the sheets opposing each other, thus forming cavities, which are filled with hay, &c., substantially in the manner set forth, and for the purposes specified.

OLIVER LONG.
